(57) **ABSTRACT**

In a multilayer coil component, first and second conductor patterns respectively have parallel parts that overlap in a lamination direction and non-parallel parts that do not overlap. The parallel parts of the first and second conductor patterns of one set are interconnected by a first through hole. The non-parallel parts of the first and second conductor patterns of sets adjacent to each other in the lamination direction are interconnected by a second through hole.

Fig.4## MULTILAYER COIL COMPONENT

TECHNICAL FIELD

The present disclosure relates to a multilayer coil component.

BACKGROUND

The multilayer inductor described in, for example, Japanese Unexamined Patent Publication No. 2013-162101 is known as a multilayer coil component of the related art. This multilayer inductor includes a laminate made of a plurality of insulator layers, an external electrode formed outside the laminate, and a coil conductor formed on a spiral in the laminate. Only two types of conductor patterns, C- and I-shaped, constitute a coil main body. The C-shaped patterns are larger in number than the I-shaped patterns.

SUMMARY

In the multilayer inductor, layers having the same conductor pattern overlap in the direction of lamination. Accordingly, the inductor is problematic in that through holes connecting the conductor patterns of the layers that are adjacent in the lamination direction are also continuous in the lamination direction at the same position and the conductor volume at the same position increases. Stress application is likely to occur at the position of conductor volume increase, and thus it is conceivable that through hole disconnection is likely to occur in the event of thermal expansion, thermal contraction, or the like.

The present disclosure has been made to solve the above problems, and an object of the present disclosure is to provide a multilayer coil component capable of suppressing the occurrence of through hole disconnection.

A multilayer coil component according to one aspect of the present disclosure includes a coil portion in an insulating element body forming a multilayer structure. The coil portion has a plurality of sets including first and second conductor pattern layers respectively having first and second conductor patterns. The first conductor pattern and the second conductor pattern respectively have parallel parts overlapping in a lamination direction, non-parallel parts not overlapping in the lamination direction, and pad portions used for inter-conductor pattern connection. In one set, first pad portions provided at the parallel part of the first conductor pattern and the parallel part of the second conductor pattern are connected to each other via a first through hole. A second pad portion provided at the non-parallel part of the first conductor pattern of the one set and a third pad portion provided at the non-parallel part of the second conductor pattern of a set positioned on one side in the lamination direction with respect to the one set are connected via a second through hole. The third pad portion provided at the non-parallel part of the second conductor pattern of the one set and the second pad portion provided at the non-parallel part of the first conductor pattern of a set positioned on the other side in the lamination direction with respect to the one set are connected via a second through hole.

In this multilayer coil component, the first through hole connecting the first conductor pattern and the second conductor pattern of one set connects the first pad portions provided at the parallel part to each other and the second through hole connecting the first and second conductor patterns of one set and the set that is adjacent to the one set connects the second and third pad portions provided at the

non-parallel part. As a result, in this multilayer coil component, the position of the first through hole and the position of the second through hole can be dispersed when viewed from the lamination direction. By dispersing the positions of the through holes, it is possible to avoid an increase in the conductor volume at the same position. Accordingly, the occurrence of disconnection of the through holes can be suppressed even in the event of thermal expansion, thermal contraction, or the like.

The second pad portion and the third pad portion may overlap in the lamination direction in the one set. Also in this case, the relationship of dispersion between the position of the first through hole and the position of the second through hole is maintained and the symmetry of the first conductor pattern and the second conductor pattern is enhanced to lead to pattern simplification.

A void may exist between layers of the second pad portion and the third pad portion in the one set. In this case, the void allows the electrical resistivity between the layers of the second pad portion and the third pad portion to be higher than that of the element body material and the withstand voltage of the multilayer coil component can be improved.

A recess may be provided in at least one of a surface of the second pad portion on the third pad portion side and a surface of the third pad portion on the second pad portion side in the one set. In this case, the recess allows a sufficient inter-layer distance to be ensured between the second and third pad portions and the withstand voltage of the multilayer coil component can be improved.

A distance in the lamination direction between the first conductor pattern and the second conductor pattern in the one set may be exceeded by a distance in the lamination direction between the first conductor pattern of the one set and the second conductor pattern of the set positioned on the one side in the lamination direction with respect to the one set and a distance in the lamination direction between the second conductor pattern of the one set and the first conductor pattern of the set positioned on the other side in the lamination direction with respect to the one set. In this case, a sufficient inter-layer distance can be ensured between the sets that are adjacent to each other in the lamination direction and the withstand voltage of the multilayer coil component can be improved.

The element body may be configured by laminating a magnetic body layer containing metal magnetic particles, and the number of the metal magnetic particles between the second pad portion and the third pad portion in the one set may exceed the number of the metal magnetic particles positioned between the first conductor pattern and the second conductor pattern in the one set. The withstand voltage of the multilayer coil component can be improved by the metal magnetic particles between the second pad portion and the third pad portion being relatively large in number.

BRIEF DESCRIPTION OF THE DRAWINGS

FIG. 1 is a perspective view illustrating an embodiment of a multilayer coil component.

FIG. 2 is a diagram illustrating the layer configuration of the multilayer coil component.

FIG. 3 is a diagram illustrating the connection relationship between first and second conductor pattern layers.

FIG. 4 is a cross-sectional view of a main part of the multilayer coil component.

DETAILED DESCRIPTION

Hereinafter, a preferred embodiment of a multilayer coil component according to one aspect of the present disclosure will be described in detail with reference to the drawings.

FIG. 1 is a perspective view illustrating an embodiment of the multilayer coil component. As illustrated in FIG. 1, a multilayer coil component 1 includes an element body 2 having a rectangular parallelepiped shape and a pair of terminal electrodes 3 and 3. The pair of terminal electrodes 3 and 3 are respectively disposed in both end portions of the element body 2 and are separated from each other. The rectangular parallelepiped shape includes a rectangular parallelepiped shape in which the corner and ridge portions are chamfered and a rectangular parallelepiped shape in which the corner and ridge portions are rounded. The multilayer coil component 1 can be applied to, for example, a bead inductor or a power inductor.

The rectangular parallelepiped element body 2 has a pair of end surfaces 2a and 2b facing each other, a pair of main surfaces 2c and 2d facing each other, and a pair of side surfaces 2e and 2f facing each other. In the following description, the direction in which the pair of end surfaces 2a and 2b face each other is a first direction D1 and the direction in which the pair of main surfaces 2c and 2d face each other is a second direction D2. In addition, the direction in which the pair of side surfaces 2e and 2f face each other is a third direction D3. The first direction D1, the second direction D2, and the third direction D3 are orthogonal to each other. In the present embodiment, the pair of end surfaces 2a and 2b have a square shape and the pair of main surfaces 2c and 2d and the pair of side surfaces 2e and 2f have a rectangular shape. The main surface 2c (bottom surface in FIG. 1) can be a mounting surface. The mounting surface faces another electronic device when the multilayer coil component 1 is mounted on the electronic device (such as a circuit board and an electronic component).

The element body 2 is configured by laminating a plurality of magnetic body layers 11 (see FIG. 2). The magnetic body layers 11 are laminated in the facing direction of the main surfaces 2c and 2d. In other words, the lamination direction of the magnetic body layers 11 coincides with the second direction D2 (hereinafter, the facing direction of the main surfaces 2c and 2d may be referred to as "lamination direction"). Each magnetic body layer 11 has a substantially rectangular shape. In the actual element body 2, the magnetic body layers 11 are integrated to the extent that the boundaries between the layers cannot be visually recognized.

The element body 2 contains a plurality of metal magnetic particles (not illustrated). The metal magnetic particles are made of, for example, a soft magnetic alloy. The soft magnetic alloy is, for example, a Fe—Si-based alloy. In a case where the soft magnetic alloy is the Fe—Si-based alloy, the soft magnetic alloy may contain P. The soft magnetic alloy may be, for example, a Fe—Ni—Si-M-based alloy. "M" contains one or more elements selected from Co, Cr, Mn, P, Ti, Zr, Hf, Nb, Ta, Mo, Mg, Ca, Sr, Ba, Zn, B, Al, and rare earth elements.

In the element body 2, the metal magnetic particles are bonded to each other. The metal magnetic particles are bonded to each other by, for example, the oxide films formed on the surfaces of the metal magnetic particles being bonded to each other. In addition, the element body 2 includes a part filled with resin. The resin exists in at least a part between the plurality of metal magnetic particles. The resin is a resin that has electrical insulation. A silicone resin, a phenol resin, an acrylic resin, an epoxy resin, or the like is used as the resin. A void part that is not filled with resin may exist between the plurality of metal magnetic particles.

Each of the pair of terminal electrodes 3 and 3 has a flat rectangular parallelepiped shape. The pair of terminal elec-

trodes 3 and 3 are disposed so as to cover the end surfaces 2a and 2b of the element body 2, respectively. The terminal electrode 3 is configured to contain a conductive material. The conductive material is, for example, Ag or Pd. The terminal electrode 3 is, for example, a baking electrode and is configured as a sintered body of conductive paste. The conductive paste contains conductive metal powder and glass frit. The conductive metal powder is, for example, Ag powder or Pd powder. A plating layer may be formed on the surface of the terminal electrode 3. The plating layer is formed by, for example, electroplating. The electroplating is, for example, electric Ni plating or electric Sn plating.

FIG. 2 is a diagram illustrating the layer configuration of the multilayer coil component. As illustrated in FIG. 2, a coil portion C is provided in the element body 2. The plurality of layers that form the coil portion C are configured to include a cover layer Lc, a first conductor pattern layer L1, a second conductor pattern layer L2, a connecting conductor layer L3, and a lead conductor layer L4. A magnetic body layer 20 containing metal magnetic particles constitutes the cover layer Lc alone. A plurality of the cover layers Lc are respectively disposed on the main surface 2c side and the main surface 2d side of the element body 2.

A conductor part is formed in a predetermined pattern in each layer except the cover layer Lc. The conductor part is made of, for example, a metal material. The material of the metal material is not particularly limited, and Ag, Cu, Au, Al, Pd, a Pd/Ag alloy, and so on can be used. A Ti compound, a Zr compound, a Si compound, or the like may be added to the metal material. A printing method, a thin film growth method, or the like can be used in forming the conductor part.

The first conductor pattern layer L1 and the second conductor pattern layer L2 form the main part (winding part) 35 of the coil portion C. In the present embodiment, one first conductor pattern layer L1, one second conductor pattern layer L2, and one connecting conductor layer L3 are laminated in this order to constitute one set. In the element body 2, a plurality of the sets are provided in the multilayer structure in accordance with the number of turns that is required in the coil portion C.

The first conductor pattern layer L1 has a first conductor pattern 12. The first conductor pattern 12 has a substantially rectangular ring shape as a whole. The first conductor pattern 12 has a first part 12a extending in the third direction D3 on the end surface 2a side, a second part 12b extending in the first direction D1 on the side surface 2e side, and a third part 12c extending in the third direction D3 on the end surface 2b side. In addition, the first conductor pattern 12 has a fourth part 12d extending in the first direction D1 on the side surface 2f side.

In the first conductor pattern 12, one end of the fourth part 12d is connected to the end portion of the third part 12c on the side surface 2f side and the other end of the fourth part 55 12d is positioned in the middle of the first conductor pattern layer L1 in the first direction D1. First pad portions 13 are respectively provided in the end portion of the first part 12a on the side surface 2f side and at the connection part between the third part 12c and the fourth part 12d. In addition, a second pad portion 14 is provided at the other end of the fourth part 12d.

The second conductor pattern layer L2 has a second conductor pattern 16. The second conductor pattern 16 has a substantially rectangular ring shape as a whole. The second conductor pattern 16 has a first part 16a extending in the third direction D3 on the end surface 2a side, a second part 65 16b extending in the first direction D1 on the side surface 2e

side, and a third part **16c** extending in the third direction **D3** on the end surface **2b** side. In addition, the second conductor pattern **16** has a fourth part **16d** extending in the first direction **D1** on the side surface **2f** side.

In the second conductor pattern **16**, one end of the fourth part **16d** is connected to the end portion of the first part **16a** on the side surface **2f** side and the other end of the fourth part **16d** is positioned in the middle of the first conductor pattern layer **L1** in the first direction **D1**. The first pad portions **13** are respectively provided at the connection part between the first part **16a** and the fourth part **16d** and in the end portion of the third part **16c** on the side surface **2f** side. In addition, a third pad portion **17** is provided at the other end of the fourth part **16d**.

As described above, in the present embodiment, both the other end of the fourth part **12d** where the second pad portion **14** is provided in the first conductor pattern **12** and the other end of the fourth part **16d** where the third pad portion **17** is provided in the second conductor pattern **16** are positioned in the middle in the first direction **D1**. Accordingly, the second pad portion **14** and the third pad portion **17** overlap in the lamination direction.

The connecting conductor layer **L3** functions as a layer that ensures an inter-layer distance between the sets of the first conductor pattern layer **L1** and the second conductor pattern layer **L2** adjacent to each other in the lamination direction. The connecting conductor layer **L3** has only a pad portion **18** as a conductor part. The pad portion **18** is disposed so as to correspond to the second pad portion **14** of the first conductor pattern **12** and the third pad portion **17** of the second conductor pattern **16**. In other words, the pad portion **18**, the second pad portion **14**, and the third pad portion **17** overlap in the lamination direction.

The lead conductor layer **L4** connects the coil portion **C** to the terminal electrodes **3** and **3**. In the present embodiment, the lead conductor layer **L4** has a lead conductor layer **L4A** disposed on the main surface **2c** side and a lead conductor layer **L4B** disposed on the main surface **2d** side. The lead conductor layer **L4A** is disposed on the lower layer side (main surface **2c** side) of the connecting conductor layer **L3** of the set that is positioned closest to the main surface **2c** side. The lead conductor layer **L4A** has a pad portion **19** disposed so as to overlap the pad portion **18** of the connecting conductor layer **L3** in the lamination direction and a lead conductor **20A** extending from the pad portion **19** toward the edge on the end surface **2b** side. The pad portion **19** is electrically connected to the pad portion **18** of the connecting conductor layer **L3** via a through hole (not illustrated). The lead conductor **20A** is connected to the terminal electrode **3** covering the end surface **2b** at the end surface **2b**.

On the main surface **2d** side, one connecting conductor layer **L3** is disposed on the upper layer side (main surface **2d** side) of the first conductor pattern layer **L1** of the set that is positioned closest to the main surface **2d** side. The lead conductor layer **L4B** has the pad portion **19** disposed so as to overlap the pad portion **18** of the connecting conductor layer **L3** in the lamination direction and a lead conductor **20B** extending from the pad portion **19** toward the edge on the end surface **2a** side. The pad portion **19** is electrically connected to the pad portion **18** of the connecting conductor layer **L3** via a through hole (not illustrated). The lead conductor **20B** is connected to the terminal electrode **3** covering the end surface **2a** at the end surface **2a**.

The connection relationship between the first conductor pattern layer **L1** and the second conductor pattern layer **L2** will be described in more detail below. FIG. 3 is a diagram illustrating the connection relationship between the first and

second conductor pattern layers. As illustrated in FIG. 3, in connecting the first conductor pattern layer **L1** and the second conductor pattern layer **L2**, the first conductor pattern **12** and the second conductor pattern **16** have parallel parts **P1** that overlap in the lamination direction and non-parallel parts **P2** that do not overlap in the lamination direction.

In the present embodiment, the first parts **12a** and **16a**, the second parts **12b** and **16b**, and the third parts **12c** and **16c** of the first conductor pattern **12** and the second conductor pattern **16** are the parallel parts **P1** and the fourth parts **12d** and **16d** are the non-parallel parts **P2**. In one set, the first pad portions **13** and **13** provided at the parallel part **P1** of the first conductor pattern **12** and the parallel part **P1** of the second conductor pattern **16** are connected to each other via a first through hole **T1**. In one set, the second pad portion **14** provided at the non-parallel part **P2** of the first conductor pattern **12** and the third pad portion **17** provided at the non-parallel part **P2** of the second conductor pattern **16** are not connected.

The second pad portion **14** and the third pad portion **17** are used for connection between one set and a set adjacent to the one set in the lamination direction. In the example of FIG. 3, the second pad portion **14** provided at the non-parallel part **P2** of the first conductor pattern **12** of one set and the third pad portion **17** provided at the non-parallel part **P2** of the second conductor pattern **16** of the set that is positioned on one side in the lamination direction with respect to one set are connected to each other via the pad portion **18** of the connecting conductor layer **L3** and a second through hole **T2**. In addition, the third pad portion **17** provided at the non-parallel part **P2** of the second conductor pattern **16** of one set and the second pad portion **14** provided at the non-parallel part **P2** of the first conductor pattern **12** of the set that is positioned on the other side in the lamination direction with respect to one set are connected to each other via the pad portion **18** of the connecting conductor layer **L3** and the second through hole **T2**.

FIG. 4 is a cross-sectional view of a main part of the multilayer coil component. Illustrated in FIG. 4 is the cross section of the element body **2** that is cut in the lamination direction at the position of a dashed line **K** illustrated in FIG. 3. Although the second pad portion **14** and the third pad portion **17** in one set are not connected as described above, a void **G** exists between the layers of the second pad portion **14** and the third pad portion **17** in one set as illustrated in FIG. 4. The void **G** can be formed by, for example, the difference in heat shrinkage between the element body **2** and the conductor part constituting the coil portion **C**. The void **G** may be formed by sandwiching a void forming member between the layers of the second pad portion **14** and the third pad portion **17** when the element body **2** is formed. In a case where the element body **2** includes a plurality of metal magnetic particles and a part filled with resin as in the present embodiment, some of the resin may be in the void **G**.

In addition, in one set in the present embodiment, a recess **21** is provided in at least one of the surface of the second pad portion **14** on the third pad portion **17** side and the surface of the third pad portion **17** on the second pad portion **14** side. In the present embodiment, the recess **21** is provided in each of these surfaces. Because of the recesses **21** and **21**, a lamination-direction distance **L1** between the second pad portion **14** and the third pad portion **17** in one set exceeds a lamination-direction distance **L2** between the first conductor pattern **12** and the second conductor pattern **16** in one set.

The recess **21** can be formed by, for example, printing a magnetic material in the same shape as the second pad portion **14** at the position of the second pad portion **14** before forming the first conductor pattern **12** on the magnetic body layer **11** by printing or the like. In addition, the recess **21** can be formed in the third pad portion **17** by disposing a magnetic material between the second pad portion **14** and the third pad portion **17** and allowing the magnetic material to enter the third pad portion **17** side in the process of laminating and crimping the magnetic body layer **11**.

In addition, in the present embodiment, the lamination-direction distance **L2** between the first conductor pattern **12** and the second conductor pattern **16** in one set is exceeded by a lamination-direction distance **L3** between the first conductor pattern **12** of one set and the second conductor pattern **16** of the set that is positioned on one side in the lamination direction with respect to one set and a lamination-direction distance **L4** between the second conductor pattern **16** of one set and the first conductor pattern **12** of the set that is positioned on the other side in the lamination direction with respect to one set. In the example of FIG. 4, each of the distance **L3** and the distance **L4**, which are equal to each other, exceeds the distance **L2** ($L2 < L3 = L4$).

In addition, in the present embodiment, the number of metal magnetic particles between the second pad portion **14** and the third pad portion **17** in one set exceeds the number of metal magnetic particles positioned between the first conductor pattern **12** and the second conductor pattern **16** (between the parallel parts **P1** and **P1**) in one set. In other words, in the present embodiment, the number of metal magnetic particles arranged in the lamination direction over the distance **L1** exceeds the number of metal magnetic particles arranged in the lamination direction over the distance **L2**. As for the number of metal magnetic particles, the average values at a plurality of positions may be compared to each other.

As described above, in the multilayer coil component **1**, the first through hole **T1** connecting the first conductor pattern **12** and the second conductor pattern **16** of one set connects the first pad portions **13** and **13** provided at the parallel part **P1** to each other and the second through hole **T2** connecting the first conductor patterns **12** and the second conductor patterns **16** of one set and the set that is adjacent to the one set connects the second and third pad portions **14** and **17** provided at the non-parallel part **P2**. As a result, in the multilayer coil component **1**, the position of the first through hole **T1** and the position of the second through hole **T2** can be dispersed when viewed from the lamination direction. By dispersing the positions of the first through hole **T1** and the second through hole **T2**, it is possible to avoid an increase in the conductor volume at the same position. Accordingly, the occurrence of disconnection of the through holes **T1** and **T2** can be suppressed even in the event of thermal expansion, thermal contraction, or the like.

In the multilayer coil component **1**, the second pad portion **14** and the third pad portion **17** in one set overlap in the lamination direction. In this case, the relationship of dispersion between the position of the first through hole **T1** and the position of the second through hole **T2** is maintained and the symmetry of the first conductor pattern **12** and the second conductor pattern **16** is enhanced to lead to pattern simplification.

In the multilayer coil component **1**, the void **G** exists between the layers of the second pad portion **14** and the third pad portion **17** in one set. With this void **G**, the electrical resistivity between the layers of the second pad portion **14** and the third pad portion **17** can be higher than that of the

element body material and the withstand voltage of the multilayer coil component **1** can be improved. In addition, in one set in the multilayer coil component **1**, the recess **21** is provided in each of the surface of the second pad portion **14** on the third pad portion **17** side and the surface of the third pad portion **17** on the second pad portion **14** side. With these recesses **21**, a sufficient inter-layer distance can be ensured between the second pad portion **14** and the third pad portion **17** and the withstand voltage of the multilayer coil component **1** can be improved.

In the multilayer coil component **1**, the lamination-direction distance **L2** between the first conductor pattern **12** and the second conductor pattern **16** in one set is exceeded by the lamination-direction distance **L3** between the first conductor pattern **12** of one set and the second conductor pattern **16** of the set that is positioned on one side in the lamination direction with respect to one set and the lamination-direction distance **L4** between the second conductor pattern **16** of one set and the first conductor pattern **12** of the set that is positioned on the other side in the lamination direction with respect to one set. As a result, a sufficient inter-layer distance can be ensured between the sets that are adjacent to each other in the lamination direction and the withstand voltage of the multilayer coil component **1** can be improved.

In the multilayer coil component **1**, the element body **2** is configured by laminating the magnetic body layers **11** containing the plurality of metal magnetic particles. The number of metal magnetic particles between the second pad portion **14** and the third pad portion **17** in one set exceeds the number of metal magnetic particles positioned between the first conductor pattern **12** and the second conductor pattern **16** in one set. The withstand voltage of the multilayer coil component **1** can be improved by the metal magnetic particles between the second pad portion **14** and the third pad portion **17** being relatively large in number.

The present disclosure is not limited to the above embodiment. For example, although the recesses **21** in the above embodiment are provided in both the surface of the second pad portion **14** on the third pad portion **17** side and the surface of the third pad portion **17** on the second pad portion **14** side, the recess **21** may be provided in only one of the surfaces or may not be provided in any of the surfaces. The void **G** between the layers of the second pad portion **14** and the third pad portion **17** does not necessarily have to be provided.

The element body **2** does not necessarily have to contain metal magnetic particles and may be made of ferrite (such as Ni—Cu—Zn-based ferrite, Ni—Cu—Zn—Mg-based ferrite, and Cu—Zn-based ferrite), a dielectric material, or the like. In addition, although one set in the above embodiment is configured by one first conductor pattern layer **L1**, one second conductor pattern layer **L2**, and one connecting conductor layer **L3**, one set may be configured by one first conductor pattern layer **L1** and one second conductor pattern layer **L2** with the connecting conductor layer **L3** omitted.

What is claimed is:

1. A multilayer coil component comprising a coil portion in an insulating element body forming a multilayer structure, wherein

the coil portion has a plurality of sets including first and second conductor pattern layers respectively having first and second conductor patterns, the first conductor pattern and the second conductor pattern respectively have parallel parts overlapping in a lamination direction, non-parallel parts not overlapping in the lamination direction, and pad portions used for inter-conductor pattern connection,

in one set, first pad portions provided at the parallel part of the first conductor pattern and the parallel part of the second conductor pattern are connected to each other via a first through hole, 5 a second pad portion provided at the non-parallel part of the first conductor pattern of the one set and a third pad portion provided at the non-parallel part of the second conductor pattern of a set positioned on one side in the lamination direction with respect to the one set are connected via a second through hole, and the third pad portion provided at the non-parallel part of the second conductor pattern of the one set and the second pad portion provided at the non-parallel part of the first conductor pattern of a set positioned on the other side in the lamination direction with respect to the one set are connected via the second through hole, and wherein a void exists between layers of the second pad portion and the third pad portion in the one set.

2. The multilayer coil component according to claim 1, 20 wherein the second pad portion and the third pad portion overlap in the lamination direction in the one set.

3. The multilayer coil component according to claim 1, 25 wherein a recess is provided in at least one of a surface of the second pad portion on the third pad portion side and a surface of the third pad portion on the second pad portion side in the one set.

4. The multilayer coil component according to claim 1, 30 wherein a distance in the lamination direction between the first conductor pattern and the second conductor pattern in the one set is exceeded by a distance in the lamination direction between the first conductor pattern of the one set and the second conductor pattern of the set positioned on the one side in the lamination direction with respect to the one set and a distance in the lamination direction between the second conductor pattern of the one set and the first conductor pattern of the set positioned on the other side in the lamination direction with respect to the one set.

5. The multilayer coil component according to claim 1, 35 wherein

the element body is configured by laminating a magnetic body layer containing metal magnetic particles, and the number of the metal magnetic particles between the second pad portion and the third pad portion in the one set exceeds the number of the metal magnetic particles positioned between the first conductor pattern and the second conductor pattern in the one set.

6. A multilayer coil component comprising a coil portion in an insulating element body forming a multilayer structure, 40 wherein

the coil portion has a plurality of sets including first and second conductor pattern layers respectively having first and second conductor patterns,

the first conductor pattern and the second conductor pattern respectively have parallel parts overlapping in a lamination direction, non-parallel parts not overlapping in the lamination direction, and pad portions used for inter-conductor pattern connection,

in one set, first pad portions provided at the parallel part of the first conductor pattern and the parallel part of the second conductor pattern are connected to each other via a first through hole,

a second pad portion provided at the non-parallel part of the first conductor pattern of the one set and a third pad portion provided at the non-parallel part of the second conductor pattern of a set positioned on one side in the lamination direction with respect to the one set are connected via a second through hole, and

the third pad portion provided at the non-parallel part of the second conductor pattern of the one set and the second pad portion provided at the non-parallel part of the first conductor pattern of a set positioned on the other side in the lamination direction with respect to the one set are connected via the second through hole, and wherein a distance in the lamination direction between the first conductor pattern and the second conductor pattern in the one set is exceeded by a distance in the lamination direction between the first conductor pattern of the one set and the second conductor pattern of the set positioned on the one side in the lamination direction with respect to the one set and a distance in the lamination direction between the second conductor pattern of the one set and the first conductor pattern of the set positioned on the other side in the lamination direction with respect to the one set.

7. The multilayer coil component according to claim 6, 50 wherein the second pad portion and the third pad portion overlap in the lamination direction in the one set.

8. The multilayer coil component according to claim 6, wherein a void exists between layers of the second pad portion and the third pad portion in the one set.

9. The multilayer coil component according to claim 6, 45 wherein a recess is provided in at least one of a surface of the second pad portion on the third pad portion side and a surface of the third pad portion on the second pad portion side in the one set.

10. The multilayer coil component according to claim 6, 50 wherein

the element body is configured by laminating a magnetic body layer containing metal magnetic particles, and the number of the metal magnetic particles between the second pad portion and the third pad portion in the one set exceeds the number of the metal magnetic particles positioned between the first conductor pattern and the second conductor pattern in the one set.
